The ornamental design for an instrument meteorological conditions simulation headwear, as shown and described.

DESCRIPTION

FIG. 1 is a front perspective view of an instrument meteorological conditions simulation headwear showing my new design;

FIG. 2 is a front perspective view thereof;

FIG. 3 is a right elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken line showing of the human form in FIG. 1 is for illustrative purposes only and forms no part of the claimed design.
